UNITED STATES PATENT OFFICE

2,425,949

COLLAR FASTENER

Estelle Mleczek, Chicago, Ill.

Application October 29, 1945, Serial No. 625,372

4 Claims. (Cl. 24—81)

1

The present invention relates to collar fasteners and has for its main object the provision of a fastener for engaging collar wings, with means therein provided for prompt disengagement.

A still further object of the present invention is the provision in a fastener of the type above indicated of means for automatic engagement of collar wings when inserted into the fastener, with means for prompt disengagement thereof.

A still further object of the present invention is the provision of a fastener having opposed pins piercing collar wings when inserted into the fastener, with means cooperating with said pins for shifting the same angularly of the body of the fastener and thereby promptly disengaging the same from the collar.

A still further object of the present invention is the provision of a fastener having a pair of spaced bars with disengageable means therebetween for engaging fabric material.

With the above general objects in view and others that will appear as the invention is better understood, the same consists in the novel construction, combination and arrangements of parts hereinafter more fully described, illustrated in the accompanying drawing and pointed out in the appended claims.

In the drawing forming a part of this application, and in which like designating characters refer to corresponding parts throughout the several views;

Fig. 1 is a top plan view of the invention;

Fig. 2 is a side elevational view thereof;

Fig. 3 is a bottom elevational view thereof;

Fig. 4 is a side elevational view of a pin constituting part of the present invention and intended for engagement with a collar wing; and

Fig. 5 is a cross-sectional view on line 5—5 of Fig. 2.

Referring in detail to the present drawing the fastener includes a front arcuate bar 10, provided at each of its free ends with decorative enlargement 11.

Cooperating with said front bar 10 is rear bar 12, which is substantially on the same plane with bar 10, and is rigidly locked thereto and centrally thereof by means of a pair of opposed tongues 13, which are bent around said rear bar 12 as is clearly seen in Fig. 3.

Said rear bar 12 is slightly longer than said front bar 10.

Said bar 12 laterally of said tongues 13 is bent away from front bar 10, effecting bulges 14 for providing spaces there between and said front

2

bar 10 wherein the vertical hems of collar wings are accommodated.

Past said bulges 14 said rear bar 12 is bent towards said front bar 10, effecting elevations 15, facing the adjacent ends of front bar 10 and substantially opposite of said enlargements 11.

Each end of said rear bar 12 has straight portion 16 which flares away from the adjacent ends of said front bar 10.

Cooperating with each end of said rear bar 12, and pivoted by its inner end thereto by means of rivet 17, is plate 18, conforming to the contour of said rear bar 12 and overlying its inner face, with the exception of bend 19, made adjacent elevation 15 and inner termination of flaring end portion 16 of said rear bar 12. Said bend 19, in the operative position of plate 18 contacts and bears against said enlargements 11 of front bar 10.

Passing through said bend 19 is pin 20, the outer end of which is doubled up as at 21 for frictionally engaging the adjacent free end of plate 18, the pin being longitudinally disposed with respect to the plate.

The inner sharp point of pin 20 extends within the space defined by, and intermediately of bulge 14 and the adjacent body portion of front bar 10, as is clearly seen in Fig. 2. As shown, the sharp point of 20' of pin 20 extends inwardly, away from the free end of plate 18.

Made longitudinally and centrally of bar 12, and coextensively with elevations 15 is recess 22 within which portion of pin 20, which is below plate 18, is adapted to spring into and be locked thereby to bar 12 when plate 18 and pin 20 are in an operative position therewith, as is seen in Figs. 1 and 5.

To use the fastener hereinabove described with a collar, each wing thereof is inserted between bend 19 and enlargement 11, at each end of the fastener, the vertical hem portion of each wing being shifted until the same is well past the sharp point 20' of pin 20. Each wing will then be engaged by pin 20 and thereby both ends of the collar will be held in a rigid engagement by the fastener so that no lateral pull upon the collar will be able to disengage the same from the fastener. In the operative position of the fastener with the collar, the front bar 10 will remain forwardly thereof, with its ends and enlargements 11 overlying the wings, while bar 12 and plate 18 will remain rearwardly of the collar wings, thereby clamping the collar wings therebetween.

To disengage the fastener from the collar the wings thereof are slightly pulled towards the center of the fastener, until pins 20 are disen-

gaged therefrom. Thereupon the free ends of plates 18 are manually shifted to spring pins 20 out of recesses 22, the position illustrated in dotted lines in Fig. 1, and said plates 18 are angularly swung as far as they will go. This operation will remove the sharp points of pins 20 out of the path of the collar wings and thereupon the fastener is removed therefrom.

From the hereinabove description it will be apparent that the fastener herein disclosed provides a simple means of holding collar wings in position, with means therein provided for positively engaging the collar wings and preventing the fastener to slip out of engagement with the collar wings until manually released from the collar wings. It will also be apparent that the ends of bars 10 and 12 need not be under a great degree of tension; in fact there may be a small gap therebetween thereby eliminating strong frictional contact with the collar wings, and thereby minimizing the wear and tear thereon.

While there is described herein a preferred embodiment of the present invention, it is nevertheless to be understood that minor changes may be made therein without departing from the spirit and scope of the invention as claimed.

What I claim as new is:

1. A fastener for fastening fabric material comprising a pair of bars in rigid mutual engagement intermediate their ends, the free ends of said bars being in a resiliently yielding mutual relation for clamping fabric material therebetween, a plate pivotally connected on one of said bars for angular movement toward and away from said bars, and a pin carried by said plate, the sharp point of said pin being disposed away from the ends of said bars for positively engaging the fabric material when the same is inserted within said bars.

2. A fastener for fastening fabric material comprising a pair of bars in rigid mutual engagement intermediate their ends, the free ends of said bars being in a resiliently mutual relation for clamping fabric material therebetween, a plate in pivotal engagement with one of said bars, said plate being provided with a bend, and a pin extending through said bend, said pin being in rigid engagement with said plate and in a longitudinal relation therewith, said one bar being provided with a longitudinal recess wherein a portion of said pin is adapted to spring into for locking said pin and said plate with said one bar when said plate remains in an operative position relative to said bars, the sharp point of said pin being disposed away from the free ends

5

of said bars for positively engaging the fabric material when the same is inserted between said bars, said plate being adapted for angular shifting movement with respect to said bars for springing said pin out of said recess for disengaging the same from its engagement with fabric material.

10

3. A collar wing fastener comprising a pair of bars, said bars being connected intermediately of their ends, the two ends of said bars being adapted to receive therebetween a pair of collar wings, a plate interposed between said bars at each end thereof, said plates being pivotally connected at one of their ends on one of said bars, a pin rigidly carried by each plate, the sharp points of said pins being directed inwardly toward said pivotal connection of said bar with said plates for simultaneously engaging a pair of collar wings, and means rigidly engaging said pins with one of said bars when said pins remain in an operative position therewith, said means being rendered inoperative on the pivotal movement of said plates with relation to said bars.

20

4. A collar wing fastener comprising a pair of bars, said bars being connected intermediately of their ends, the two ends of said bars being adapted to receive therebetween a pair of collar wings, a plate interposed between said bars at each end thereof, said plates being pivotally connected at one of their ends on one of said bars, a pin rigidly carried by each plate, the sharp points of said pins being directed inwardly toward said pivotal connection of said bar with said plates for simultaneously engaging a pair of collar wings, and means rigidly engaging said pins with one of said bars, said means comprising a recess formed in one of said bars, said recess being adapted to engage said pins intermediate their end portions when said pins are in their operative positions, said pins being rendered inoperative when said pins are withdrawn from said recesses and pivoted on said bar.
